[57] **CLAIM**

The ornamental design for a hand-held fan, as shown and described.

DESCRIPTION

FIG. 1 is a front perspective view of a hand-held fan showing a first embodiment of my design;

FIG. 2 is a front elevational view thereof, the rear elevational view being a mirror image thereof;

FIG. 3 is a top plan view thereof;

FIG. 4 is a bottom plan view thereof;

FIG. 5 is a left elevational view thereof, the right side being a mirror image thereof; and,

FIG. 6 is a front perspective view of a second embodiment, the rear view being plain and unornamented.

The top, bottom and sides being identical to FIGS. 3-5 of the first embodiment.
